ELIAS T. FORD, OF STILLWATER, NEW YORK.

Letters Patent No. 92,180, dated July 6, 1869.

IMPROVEMENT IN PACKING PUMP-PISTONS.

The Schedule referred to in these Letters Patent and making part of the same.

To all whom it may concern:

Be it known that I, ELIAS T. FORD, of Stillwater, in the county of Saratoga, and State of New York, have invented new and useful Improvements in Pumps; and I do hereby declare that the following is a full and exact description of the same, reference being had to the accompanying drawings, and to the letters of reference marked thereon.

This invention relates to an improved pump-plunger, and consists in the peculiar construction of the casing which surrounds a rubber disk, which forms the expanding portion of the plunger, as will be fully described hereinafter.

In the drawings—

Figure 1 represents a perspective view of a pump, to which my plunger is applied.

Figure 2, a perspective view of the plunger, detached.

Figures 3, 4, and 5, views of parts detached.

To enable others skilled in the art to which my invention appertains, to make and use the same, I will now proceed to describe fully its construction and operation.

J represents the plunger-rod, which is suitably provided with screw-threads, as shown.

D represents a disk of rubber, which is perforated, in order to slip over the plunger-rod.

C represents a metal casing, which is cut open upon one side, as shown in fig. 5. It will be observed that this cut is not made straight across the face of the

casing, nor is it made in a diagonal line, as is common, but one end is provided with the tongue b, and the other with the socket c.

F F represent metal disks, which are located above and below the rubber disks, and are secured, by means of nuts, in the usual manner.

The plunger, when put together ready for use, is represented in fig. 2.

The operation will be readily understood.

When it is desired to expand the plunger to fit the cylinder, the nut V is screwed down, and the rubber disk thereby expanded.

This operation necessarily opens the casing C more or less, but not sufficiently to withdraw the tongue b from the socket c. A tight joint is therefore always secured.

I am well aware that plungers quite similar to mine have been used, but I am not aware that a metal casing, with a tongue and socket, has before been used.

Having thus fully described my invention,

What I claim as new, and desire to secure by Letters Patent, is—

In the plunger J, having the expanding-disk D, the metal casing C, with tongue b and socket c, when arranged as described, for the purpose set forth.

ELIAS T. FORD.
